WINDOW SASH CONTROL DEVICE

Nicholas C. Leidgen, Lansing, Mich., assignor, by
decree of distribution, to Mildred Leidgen

Application August 31, 1943, Serial No. 500,627

1 Claim. (Cl. 20—69)

This invention relates to a combination weather strip and window sash control construction, intended to prevent the entrance of cold air when the sash is down, and which will hold the sash in any raised or lowered position and permit the easy movement of the sash by hand.

More particularly, this invention is an association of sash weatherstripping and sash control devices having special construction and arrangement as set forth in this specification. It is believed that the structure and disposition of the parts described in this application will reduce the amount of metal needed in window sash controls and do away with the use of sash weights and cords, thereby lessening the cost of manufacture of like window control devices.

Of the accompanying drawing intended to illustrate this invention and forming a part of this application, Fig. 1 is a front view of a lower window sash and frame with this invention applied thereto.

Fig. 2 is a horizontal sectional view of a portion of the window frame and sash taken on the line 2—2 of Fig. 1.

Fig. 3 is a horizontal sectional view of a portion of a window frame and sash taken on the line 3—3 of Fig. 1.

Fig. 4 is a top plan view of one of the grooved, resilient metal pieces hereinafter described.

Fig. 5 represents a sectional view lengthwise of the metal piece shown in Fig. 4.

Throughout the drawing and description the same number is used to refer to the same part.

The window frame 1, sill 2 and glass 3 may be of any usual construction. The applicant does not intend to limit the construction of those parts in any manner.

The sash 4 is of the proper structure and size to be raised and lowered in the frame referred to.

Considering Figs. 4 and 5, there is illustrated an important feature of this invention comprising a continuous, unitary piece of spring metal constructed with a longitudinal groove 5 and side flanges 6. As shown in Fig. 3 the flanged sides of the piece are secured to the sash 4 by nails

7 or screws of common form. The spring metal pieces are usually the same in length as the sides of the sash to which they are attached. The grooved portion of the piece is intended to have the length of weatherstripping secured therein in any manner. The number 8 refers to the weather strip in Fig. 3.

It will be understood from Fig. 4 that the view is taken looking into the longitudinal groove 5 which is continuous for the length of the piece. As illustrated in both Figs. 4 and 5 two portions near the ends of the piece are partly detached from the flanges of the piece and formed into raised springs 9. Usually there is only the two 15 curved raised springs 9, but it may be advantageous and necessary in some windows to have more than two spring elements 9 formed in the flanges of each piece. If the grooved middle 5 of the metal piece is inserted in the groove in 20 the sash, with the weatherstrip 8 therein, the integral springs 9 of the pieces will press against the frame 1 and hold the sash in any raised position. In other words, a single piece of spring metal attached on each side of the sash, with a 25 series of curved springs formed in the piece holds the sash in any raised position, carries the weatherstrip, and the only necessary weatherstrip is that held by the metal piece in the side of the sash, and moving up and down with the 30 sash.

Having now described this invention, I claim:

In a combination weather strip and window sash control apparatus, a sash having a vertical groove on each side, continuous longitudinally 35 grooved pieces of spring metal each having side flanges attached to the sides of the sash, the grooved portions engaging the grooves in the sash, said pieces of spring metal being constructed with spaced curved resilient portions having one 40 end separated from the continuous piece and arranged to press against the window frame, and weather stripping attached in the grooves of said pieces of metal and arranged to move up and down with the sash.

NICHOLAS C. LEIDGEN.
